UNITED STATES PATENT OFFICE

JAMES P. RODGERS, OF PITTSBURGH, PENNSYLVANIA, ASSIGNOR TO ELLIOTT COMPANY,
OF PITTSBURGH, PENNSYLVANIA, A CORPORATION OF PENNSYLVANIA

TUBE CLEANER

Application filed January 16, 1930. Serial No. 421,256.

The present invention relates broadly to the art of tube cleaning apparatus and more particularly to an improved form of cleaner for this purpose.

5 By my invention I provide an improved tube cleaner having pivotally mounted cleaning elements adapted to swing outwardly due to centrifugal force and by a series of blows loosen the scale or deposit on the inside of 10 the tube.

I provide a tube cleaner of such a character that it has the advantage of simplicity and rigidity and is capable of ready and easy assembly. I also provide a means of limiting 15 the outthrow of the cleaner carrier arms and for the close positioning of the cutters and carrier arms in reference to the head.

I further provide a simple and efficient 20 means which serves a double function of holding the parts of the head together and attaching the head to a driving means.

In the accompanying drawings there is 25 shown for purposes of illustration only one embodiment of the present invention, it being understood that the drawings do not define the limits of the invention as changes may be made in the construction and operation therein disclosed without departing from the spirit 30 of the invention or the scope of the broader claims.

In the drawings:

Fig. 1 is a side elevation of the cleaner showing the parts in assembled relationship and in operative position on a driving member;

Fig. 2 is a transverse sectional view along the line A—A of Fig. 6, looking in the direction of the arrows;

Fig. 3 is a longitudinal sectional view of 40 a cleaner element carrier arm with the cutters or cleaning elements located thereon;

Fig. 4 is a transverse sectional view on the line B—B of Fig. 1, looking in the direction of the arrows;

Fig. 5 is a transverse sectional view along the line C—C of Fig. 1, looking in the direction of the arrows;

Fig. 6 is a front end view of the tube cleaner as illustrated in Fig. 1;

Fig. 7 is a rear end view of the cleaner as 50 illustrated in Fig. 1.

In accordance with the present invention there may be provided an elongated cleaner head 2 of a generally triangular section. Immediately adjacent each end of the central triangular portion 3 of the head 2, which portion I call a spider, are located integral shoulders 4 which are of a generally triangular section, the purpose of which will be more fully discussed hereinafter.

On one end of the head 2 is located an integral cutter or cleaning element carrier arm support or flange 5 having spaced openings 6 therein adapted to receive the pivots 10 of the carrier arms 11 and support them for 55 swinging movement.

Near the other end of the head 2 and an integral part thereof and adjacent a shoulder 4 is located a square neck 12 which is adapted to receive and support a keeper 13 and position it with respect to the cutter arm 70 support 5 and prevent relative rotation between the keeper and the head. The head 2 adjacent the neck 12 is further provided with a threaded section 14 for the reception of the nut 15 which holds the keeper 13 in 75 place on the neck 12.

The nut 15 is of such a character that it not only serves to hold the keeper 13 in place on the neck 12 but also serves as a connection 80 between the entire head 2 and the drive shaft 16 of the driving means, said drive shaft being provided with a threaded portion 17 adapted to fit into the threaded portion 18 of the nut.

The keeper 13 is a plate having holes 19 85 spatially located therein for the reception of pivots 20 of the cutter arms 11, said openings being of such a character as to support the one end of each of the arms 11 for swinging movement. The keeper is also provided with a centrally located square opening 21 adapted to receive the neck 12 and be supported thereby. The neck 12 and the opening 21 of the keeper are of such a character as to definitely locate the holes 19 of the keeper 90 with respect to the holes 6 in the carrier arm support 5.

The cutter carrier arms 11 are each provided with pivots 10 and 20 located on opposite ends thereof and adapted to cooperate 100

with the openings 6 and 19 respectively in the support 5 and the keeper 13. Each of the arms 11 is also provided with spaced projections 22 and 23 having openings 24 and 25 respectively located therein for the reception of a cutter pin 26. Each pin 26 has a forwardly converging enlargement 27 on the end thereof with the sides 28 cut off flat for reception of a wrench or other tool for the 10 installation or removal of the pin.

Each pin 26 is adapted to receive a generally conically shaped cleaning element or cutter 29 adapted to rotate thereon and to directly abut at one end against the shoulder caused 15 by the enlargement 27 and at its opposite end engaging a washer 30 surrounding the pin. Each pin with its element 29 and washer 30 thereon is passed through an opening 24, and washers 31 and cutters 32 are alternately placed thereon. Each pin 26 has a 20 threaded end 33 adapted to cooperate with the threaded portion 34 of one of the openings 25 and hold the pin solidly in place in the carrier arm. The threaded end 33 of 25 each pin 26 has a slot 35 therein for the reception of a tool for removing or installing the cutter pin and the cutters located thereon.

As it will be noted in Fig. 3 of the drawings, the threaded ends of the pins 26 are protected 30 from any abrasive action by the openings 25. As will be noted further, the whole of each pin 26, with the exception of the forwardly converging enlargement on the front end thereof, is protected from abrasive action.

35 Each of the cutter arms 11 is provided with spaced projections 36 for cooperating with the shoulders 4 for the purpose of limiting the arcuate distances through which the arms 11 travel in an outwardly direction. When 40 the head is revolved the arms 11 are thrown outwardly and are limited in their outward movement by the integral shoulders 4 by the bearing of the projections 36 on the shoulders 4. This method of limiting the outward 45 throw of the arms 11 is an important feature of my invention.

The spider 3, as stated hereinbefore, is of generally triangular section, and as is apparent from Figs. 5 and 6, is of a smaller 50 cross-sectional area than the cutter arm support 5 or the keeper 13. This permits the close positioning of the cutters and cutter arms to the center of the head of the cleaner.

In the assembly of the improved cleaner 55 head which I provide, the pivots 10 of the arms 11 are inserted in the openings 6 in the carrier arm support 5. The keeper then is moved forward onto the head, and due to the square neck 12 on the head and the square 60 opening 21 in the keeper it is properly positioned with respect to the support 5 in that the holes 19 in the keeper are properly indexed with reference to the holes 6 in the carrier arm support. As the keeper is moved 65 onto the neck 12, the openings 19 receive

the pivots 20 of the arms 11 and support the adjacent ends thereof. The nut 15 is then placed on the threaded section 14 of the head, thereby affixing the keeper to the head. The nut 15 also receives the threaded section 17 70 of the drive shaft 16 which is used for the rotation of the cleaner head.

I claim:

1. In a tube cleaner, a head having a body portion, a cleaning element carrier having spaced projections thereon having openings therein receiving a pin for supporting a cleaning element, means on the head for supporting one end of the carrier for swinging movement, a demountable keeper, means on the head for receiving and positioning the keeper, means in the keeper for supporting the other end of the carrier for swinging movement, a threaded section on one end of the head, means on the threaded section for holding the keeper in place and engaging the driving means, and spaced shoulders on the head for limiting the distance through which the carrier swings. 75

2. In a tube cleaner, a head, a flange on one end thereof, a unitary cleaning element carrier arm, means on said flange for supporting one end of the cleaning element carrier arm for swinging movement, and a demountable keeper on the other end of the head adapted 90 to support one end of the carrier arm for swinging movement. 95

3. In tube cleaning apparatus, a plurality of cleaning elements, and a cleaning element carrier arm having supporting pivots on each 100 end thereof and having downwardly extending projections on each end having openings therein receiving a pin for supporting the cleaning elements. 105

4. In tube cleaning apparatus, a plurality of cleaning elements, and a cleaning element carrier arm having pivots on each end thereof and having downwardly extending projections on each end having openings therein receiving a pin for supporting the cleaning elements, one of said openings being threaded to cooperate with a threaded portion of the pin. 110

5. In a tube cleaner, a head having a flange on one end thereof having a plurality of bearings therein, a neck on the other end of the head, a keeper adapted to fit said neck and be supported thereon, said keeper having a plurality of bearings therein, a plurality of unitary cleaning element carrier arms, pivots on each end of the carrier arms, said pivots being adapted to cooperate with the bearings in the flange and the keeper for supporting the carrier arms and whereby the arms may be rotated on said pivots relative 120 to the head. 125

6. In a tube cleaner, a head having a flange on one end thereof and a neck portion on the other end, a cleaning element carrier arm having a pivot at each end thereof, a de- 130

mountable keeper adapted to fit on and be supported by said neck portion, and bearings in said keeper and said flange adapted to receive said pivots and support the carrier

5 for swinging movement about said pivots.

In testimony whereof I have hereunto set my hand.

JAMES P. RODGERS.
